UNITED STATES PATENT OFFICE

THEODORE BAKER, OF STILLWATER, NEW YORK, ASSIGNOR TO HOWARD P. MOSHER, OF SAME PLACE.

PAPER-BAG MACHINE.

SPECIFICATION forming part of Letters Patent No. 373,876, dated November 29, 1887.

Application filed July 5, 1883. Serial No. 100,022. (No model.)

To all whom it may concern:

Be it known that I, THEODORE BAKER, of the village of Stillwater, county of Saratoga, and State of New York, have invented a new and useful Improvement in Paper-Bag Machines, of which the following is a specification.

My invention relates to certain improvements in paper-bag machines, and more particularly to such as make bags from a single strip of paper doubled in the middle and the flaps pasted together for closing the sides and forming the bottom, with the united edges of the outfold attached on one side to the entrant fold.

In the accompanying four sheets of drawings, forming a part of this specification, there are shown ten figures illustrating a machine for making paper bags, which machine contains my improvements, with the same designation of parts by letter-reference used in all of them. Figure 1 illustrates a longitudinal central vertical section taken through the machine and its parts. Fig. 2 represents a top view of the machine, and Fig. 3 an elevation taken from the delivery end of the apparatus, and Fig. 4 an inclined vertical section taken on the line $x^1 x^1$ of Fig. 1. Fig. 5 illustrates in perspective the cutter-roller removed from the machine, and Fig. 6 shows one of the paste-conveyers as removed from the apparatus. Fig. 7 illustrates in perspective, in an enlarged proportion, as removed from the machine, a tilting table made with a fold-plate, guiding and folding fingers for producing in each side of the strip from which the bags are made an opposite half of the entrant fold. Fig. 8 shows a cross-section of said tilting table and connected parts, taken on the line $x^3 x^3$ of Fig. 7. Fig. 9 is a perspective of the bag made by the machine; and Fig. 10 is a cross-section of the same, taken on the line $x^4 x^4$ of Fig. 9.

The several parts of the apparatus thus illustrated are indicated by letter-reference, and their function is explained as follows:

The letter P designates a paper-roller hung in bearings, and from which roller the paper is supplied to the machine in a continuous strip, A^2 .

The letter R' indicates a roller, actuated as will be subsequently described, over which the strip of paper coming from the roll P first passes.

The letter F' designates a folding-plate, over and along which the strip of paper moves after having left the roller R' to pass around the pressing and folding roller a' . The latter roller has its bearings in the two vertical studs S S, and its length between its bearings is less than the width of the entering strip, so that as the latter enters between the studs S S to pass around the roller a' a fold is turned on its edges by the combined action of the studs, the fold-plate F', and the roller a' , the fold thus made being turned downwardly and inwardly, and as thus made constitutes the out-fold of the subsequently-formed entrant fold. From the pressing and folding roller a' the strip passes under and over the roller a^2 , which latter also has its bearings in the studs S S, and from the roller a^2 the strip moves over the roller R² to pass under the guide-roller R³ and from thence beneath the spring fold-plate F². When the strip commences to move beneath the last, which is narrower than the strip and made to have the requisite width for the bag, the finger-form folders $d' d'$ engage with and turn in the sides of the strip, and produce oppositely on each of them a half of the entrant fold, the edges of the strip having been pasted for union during their passage, as will hereinafter be described.

The roller R³, the spring fold-plate F², and the finger-form folders $d' d'$ are attached to and constructed on the tilting table T. The last is made with trunnions or journals J J, which turn in bearings O O, made in the machine-frame F⁶, so that this table at its end t is free to move up and down for adjustment to the tension of the strip. After each half of the entrant fold and the outfold on each inner side of the latter have been produced, the strip passes between the upper cutting-roller, C', and the lower roller, C². The roller C' contains a serrated knife, K, constructed to be moved outwardly and inwardly in a groove or passage-way, g, made in its face parallel to the axis of said roller, as will subsequently be more fully described. The roller C² contains

a groove, u , adapted for the entrance of the serrated knife, and the two rollers $C' C'$, being connected by the gears $g^2 g^2$, move together, and in their rotation the serrated knife is made 5 to descend into the groove in the lower roller to sever the intermediately-placed strip.

Upon the circumferential face of the roller C' there is placed a projecting blade, e , having a dull edge, which is arranged parallel to 10 the axis of said roller, and on the roller C' , parallel with the axis thereof and arranged so as to come in contact in revolution with the blade e , is a rubber cushion, b . When the blade e and the rubber cushion b come together 15 as the two rollers $C' C'$ rotate, there is imprinted into the passing strip a transverse fold-line, on which the end fold of the bag is subsequently produced.

Adjacent to the rubber cushion b , and so as 20 to immediately follow it in rotation, are placed the prick-awls $h h$, which are attached to and made to project from the surface of the roller C' . These awls during the rotation of the two 25 geared rollers run in the recess I , made circumferentially on the face of the roller C' , so as to prick into the intermediately-passing strip on the edge of said recess.

The letter M indicates a cushioned roller 30 having its bearings in the brackets $B^3 B^3$ and arranged parallel to the roller C' . When the strip 35 passing between the rollers C' and C^2 reaches the point where the impress for the transverse fold is to be made and has passed it, the awls $h h$ pierce the strip, so as to make it adhere to 40 the roller C^2 where punctured, and thus carry it down between the rollers M and C^2 , doubling the strip back on itself, as indicated by the dotted line a^5 of Fig. 1, with its previously-pasted edges in impressed contact to 45 unite them, while the rotation of the roller C' brings the knife K around to sever the strip as its outer end is being folded to produce a bag. The bag, after being thus folded and cut, is drawn down by the roller C^2 as thereon 50 held by the awls until the comb E , which is provided with the slots $w w$, strips the bag from off the roller. The comb E is attached to the end of the machine, with its upper edge in contact with the surface of the roller C^2 , so 55 that the edge of the comb thus placed under-runs the bag, and the awls, when passing down with the rotation of the roller, are pulled from out the bag and the bag from off the roller.

The holes made in the bag by the awls do 60 not injure it, because they are made so near the outer edges of the bag that they are covered by those portions of the bellows-folds that turn in and lie over the bottom when the bag is distended for use.

65 The letters $L' L'$ indicate paste-conveyers that are made to run in the paste-pans $l' l'$ and arranged on the same shaft as the rollers R' . Their edges are in the form of a semicircle having a peripheral measurement equal to the length of the bag that is to be produced by 70 folding the web back on itself. These pasters

75 L' as they rotate apply the paste to alternately-opposite portions of the web-edge, and then skip portions of it as they are rotated, the portions which they oppositely paste and omit being equal in length to that of the bag. The edges thus pasted are then turned down, 80 as well as the unpasted portions, when the web is passing over the edge of the form-plate F' , and over and under the rollers $a' a'$ between the 85 studs $S S$. When this has been done, the web in passing has produced in each side of it one-half of the entrant side fold. The pasters L^2 90 L^2 are also semicircular in form and adapted to rotate with the roller R^2 , so as to receive paste from the pans $l' l'$, and these pasters are set nearer together than the pasters L' , and are so rotated as to oppositely apply paste to that portion of the outfold which is folded down but not pasted onto the web. After 95 these portions of the web-edges have been pasted, then these pasters L^2 , by their form, skip or omit to paste the opposite sides of the web for a bag-length, so that when the web is folded back on itself as thus pasted the first 100 fold of the outfold adheres to the body with the other edge of the outfold pasted to it, but free from the body.

105 The cutter-roller C' has a groove or passage-way, g , made in its circumferential face parallel to its axis for the outward and inward passage and movement of the serrated knife K , and this knife outside of the roller ends is attached to the studs $A A$, of which there is one at each end of the roller, and each of which is made with the outcurve q , so as to pass around the roller-shaft S^4 . These studs are constructed to move in guideways at each end of the roller indicated at i , and each of which 110 studs is made with an offset arm, a^6 , projected therefrom, and to each of said arms, on its interior face, there is attached a spring-rod, r . On each of these rods there is arranged a helical spring, O^7 , each of the inner ends of which 115 springs is connected with a stop, O^2 , as they are arranged at each end of said roller C' . As thus constructed and attached, the knife K is forced outwardly from the groove or passage-way against the force of the spring and returned by the latter when the force applied to 120 the knife is withdrawn.

125 To operate the knife there are attached to the shaft S^4 , outside of the roller C' , the two disks D^3 , and on the perimeters of the latter there are made the cams $C^4 C^4$, each of which is arranged in opposite coincidence with the other. These cams have abrupt terminations, as indicated at v^2 .

130 The letters $H H$ designate two hammers having their handles attached to the shaft S' , the said shaft having its bearings in the brackets $B^4 B^4$, and the striking toe ends of said hammers being adapted to engage with the surfaces of the cams $C^4 C^4$ to run thereon as the latter are rotated, and to fall therefrom 135 when the abrupt terminations are passed, and in falling to strike the adjacent ends of the

studs A A, to the lower end of which is attached the serrated knife K, thus forcing the latter out of the roller C' down into the coincident groove u made in the roller C² and sever the intermediately-placed strip. When the hammers have forced down the studs by striking the ends of the latter, (made to project above the edges of the disks D³ at that point,) the hammer ends engage with the disks D³ and are arrested in their descent thereon, so that the force of the blow is in part expended on the edges of said disks, and the distance that the stud and connected knife are moved is uniformly regulated thereby.

15 To actuate the machine power is applied to the pulley P³ on the shaft S⁵. At the opposite end of said shaft are constructed the beveled gears W' W', which communicate motion to the shaft U. Upon the latter and the shaft of 20 the roller R² are arranged the gears W² W² to operate the said roller, and upon the shaft U and the shaft of the roller R' are applied the connecting beveled gears W³ W³, which communicate motion to the latter roller. The exterior face of the roller M is cushioned at m², so that while it and the roller C² are folding the strip back on itself to unite its pasted edges and complete the bag the awls on the roller C² may enter the cushion where passing through 30 the bag without interfering with the necessary impressing contact of the roller-surfaces.

The spring fold-plate F² is made to have the same width as that at which it is desired to fold the bag, and this fold-plate is attached on its upper surface to one end of a C-form spring, d³, with the other end of the latter connected to the tilting table T. The finger-form folders d' d' are also constructed to attach to the said table at their inner ends, and so as to be thereat in 40 advance of the plate F² so far as relates to an engagement with the entering strip, and where thus attached to be wider apart than the width of said fold-plate F². From where attached to the table T the folders d' d' curve inwardly and 45 upwardly for a short distance, and therefrom, as extended rearwardly, they approach each other until a proper degree of separation is made to produce the entrant fold in the sides of the passing strip. The spring fold-plate F² 50 at its front where meeting the inward movement of the strip, as indicated at y, is slightly curved upwardly. The table T, being hung on journals, as before described, sustains all the factors which produce the entrant fold, 55 and the spring-plate F², being automatically adjustable on the said table by means of the spring d³, the combined parts thus constructed and arranged readily and promptly adapt their operation to the tension of the strip thus 60 passing.

I am well aware that a cutter has been arranged with a serrated knife constructed to be moved diametrically outwardly and inwardly from said roller, and these parts have 65 been combined with a connected roller con-

taining a coincident groove for the passage of said knife to thus sever a strip of paper.

I am also aware that awls have been used in a roller to draw downwardly between said roller and another roller a folded strip of paper to double the latter back on itself to produce a bag.

I am also aware that my invention herein, so far as relates to the foregoing elements disclaimed as old, is limited to the improvements 75 that I have made thereon and added thereto, and I make no claim to the combination, with the roll and its severing-blade, of the hammers and the means, substantially as described, for actuating them.

I am also aware that a paper-bag machine has been made with a pasting and folding mechanism, consisting of disks for applying a series of short lines of paste to the edges of the web and means for folding over said edges, 85 disks for applying lines of paste to the folded edges, and a former and fingers for folding over the edges of the web a second time, and I do not broadly claim such combination.

Having thus described my invention, what I 90 claim, and desire to secure by Letters Patent, is—

1. In a paper-bag machine, the combination of the roller C', formed with the recess I, and the roller C², geared to the roller C' and 95 provided with awls h h, with the roller M, provided with the elastic covering m², substantially as and for the purpose set forth.

2. The combination, in a paper-bag machine, of the roller C', the serrated knife K, constructed to operate in said roller, as shown, the curved studs A at each end of said roller, the guideway i at each end of said roller, the offset arm a⁶ on each of said studs, a spring-rod and encircling spring attached to each 105 arm, and a stop on each spring connected with the end of the roller, as and for the purposes set forth.

3. In a paper-bag machine, the combination of the fold-plate F², having turned-up 110 end y, the spring d³, and the finger-form folders d' d', arranged to operate in the manner herein described.

4. In a paper-bag machine, the combination of the plate-folder F², the spring d³, the 115 finger-form folders d' d', and roller R², arranged to operate in the manner as and for the purposes set forth.

5. In a paper-bag machine, the combination of the plate-folder F², the spring d³, the 120 finger-form folders d' d', the guide-roller R², and the table T, connected by journals with the machine-frame, as and for the purposes set forth.

6. The combination of the roller R', the 125 paste-conveyers L' L', fixed on the shaft of said roller, the fold-plate F', the rollers a' a², shorter than the width of the bag-strip, the vertical studs S S, the roller R², and the paste-conveyers L² L², all substantially as specified.

7. In a paper-bag machine, the combination of the roller C', formed with the recess I, the roller C², geared to the roller C' and provided with the awls h h, the roller M, provided with the elastic covering m², and the comb E, formed with the slots w w, substantially as and for the purposes set forth.

Signed at the city of Troy this 2d day of July, 1883, and in our presence, whose names are hereto below by us written.

THEODORE BAKER.
